MANIFOLD ASSEMBLY

John R. Keeley, Chicago, Ill., assignor to International Tag & Salesbook Company, Chicago, Ill., a corporation of Illinois

Application May 19, 1941, Serial No. 394,133

7 Claims. (Cl. 282—23)

The present invention relates to manifold assemblies and more in particular to manifold assemblies so constructed and arranged as to facilitate the taking of two independent inventory counts as a check against each other.

Among the objects of the present invention is to provide a novel manifold assembly comprising an original and a copy record sheet disposed in superimposed relation and so constructed and arranged that inscriptions can be transferred through the medium of transfer material provided on the original record sheet to the copy record sheet and other comparative inscriptions can be recorded on the original record sheet adjacent thereto, and wherein the said sheets are secured together on opposite sides of the transfer material and have weakened severance lines inwardly of the securing means so that the two sheets may be severed or detached along the same to present in assembled relation a part of said original and copy sheet to present said inscriptions in side by side relation for comparative purposes such, for example, as is highly desirable in making duplicate inventory counts, and the like.

The present invention includes as an object the provision of two superimposed sheets of material, one being provided with an area forming an original record sheet and another portion thereof serving as a transfer sheet provided with transfer material, and the other of said record sheets being disposed in transfer relation to said transfer material for receiving inscriptions therethrough, the said sheets being secured together substantially throughout their width on opposite sides of the transfer material and having weakened severance lines inwardly of the securing means whereby the original record sheet and a portion of the copy record sheet attached thereto may be quickly severed from the transfer sheet and a portion of the copy record sheet attached thereto when the operator grips the assembly along a marginal edge thereof at said securing means and applies an outward force thereto so that comparisons may be readily made as between the inscriptions appearing on the original record sheet and the copy record sheet.

As a further object of the present invention, the assembly as above set forth may embody in its construction blank copy disposed on the transfer sheet and above the transfer material to prevent an operator, in recording a second inventory count upon the original record sheet, for example, from securing any information in respect to the inscriptions appearing on the copy

record sheet which have been transferred through the transfer material.

The present invention further includes as an object the provision of a copy record sheet with a portion foldable in respect to the transfer sheet and in superimposed relation thereto constituting an original record sheet for receiving inscriptions to be transferred to the copy record sheet and which may have weakened severance lines at or adjacent the fold whereby said original record sheet may be readily removed from the remaining assembly so as to deprive an operator making a second inventory count, for example, of this information.

Other objects, features, capabilities and advantages are comprehended by the invention, as will later appear and as are inherently possessed thereby.

Referring to the drawing:

Figure 1 is a plan view of a manifold assembly made in accordance with the present invention and having parts broken away to show certain elements thereof more in detail;

Figure 2 is a view in cross-section taken in the plane represented by line 2—2 of Figure 1 of the drawing;

Figure 3 is a plan view of the assembly shown in Figure 1 of the drawing, with a part thereof folded into operative position for use;

Figure 4 is a view in plan of the device shown in Figure 1 of the drawing, with a part thereof detached therefrom and further having parts broken away to disclose the structure of the assembly more in detail; and

Figure 5 is an exploded view of the device as shown in Figure 4 of the drawing, disclosing more in detail the parts of the assembly in detached relation to one another, all in accordance with the present invention.

Referring now more in detail to the drawing, a manifold assembly selected to illustrate the present invention is shown as comprising two record sheets 2 and 4 disposed in overlapping relation and being secured together adjacent the overlapped marginal edges, as at 6 and 8, by means of some suitable mucilaginous material. These record sheets 2 and 4 are preferably formed from paper or the like, and in the present illustration the assembly is particularly adapted for use in connection with recording inventory counts, where it is desirable to have the first inventory count checked by another individual in the organization and independently of the first. The assembly therefore has certain printed forms appearing on the sheets 2 and 4 so arranged as to facilitate

these inventory counts, although it is to be clearly appreciated that the assembly embodying the invention herein described may be used for various purposes other than that specifically suggested.

The record sheet 4 has a portion thereof provided with form 10 constituting an original record sheet 11 adjacent which is the portion 12 disposed in overlapping relation to record sheet 2 which constitutes a transfer sheet provided with transfer material, such as carbon or the like 14, secured to the face of the sheet immediately adjacent the record sheet 2.

The record sheet 2 is formed with a portion 16 which constitutes that part of the record sheet 15 2 overlapped by record sheet 4 serving as a copy record sheet for receiving inscriptions, as will be later more fully described, through the transfer material 14. This copy record sheet 16 is provided with a suitable form, such as 18, which in the present instance is so designed as to facilitate inventory count. The record sheet 2 is further formed with a portion 20 constituting an original record sheet which is connected to the copy record sheet 16 by a weakened severance line 22 and which may be folded in superimposed relation to the transfer sheet 12. This original record sheet 20 has printed on its outer face form 24 which conforms in design to forms 10 and 18 to facilitate the recording of inventory counts and for which the disclosed assembly is particularly adapted. The form 24 is so arranged in respect to the sheet 20 as to be disposed above the transfer material 14 on the transfer sheet 12 so that inscriptions, such as 26, made upon this sheet are transferred through the transfer material to form 18 on the copy record sheet 16.

In the present assembly the transfer sheet 12 above the transfer material 14 has a blank copy thereon represented by a plurality of solid circular characters such as 28 which are placed thereon to prevent the operator making the second inventory count, as will be hereinafter more fully explained, from securing any information with respect to the inscriptions which have been transferred to the copy record sheet 16.

To facilitate the use of the device as contemplated, the copy record sheet 16 is provided with a weakened severance line 30 extending throughout the width of the said sheet and which is inwardly of the securing means 6 and on one side of the transfer material 14. In addition, the record sheet 4 is provided with a weakened severance line 32 extending throughout the width of said sheet which is disposed inwardly of the securing means 8 and on the other side of the transfer material 14 to provide an assembly whereby the transfer sheet 12 may be readily detached from the original record sheet 11.

As clearly shown in Figure 5 of the drawing, that part of the copy record sheet 16 attached to the transfer sheet 12 can be readily detached from the original record sheet 11 and that part of the copy record sheet 16 attached thereto by tearing the assembly along the weakened severance lines 30 and 32.

The assembly as above described is particularly adapted for use in connection with the taking of inventory count where it is desirable to take two independent counts as a check against each other. At the time inventory is to be taken, one operator records his inventory count upon form 24 on the original record sheet 20 when in folded condition, as clearly shown in Figure 3 of the drawings, after which recordation this

operator will detach the original record sheet 20 from the remaining parts of the assembly along the weakened severance line 22. The manifold assembly is then turned over to a second operator for a count. This second operator then makes his count of inventory and records the same as 34, in the proper space of form 10 appearing on the original record sheet 11. It is to be understood, of course, that these recordations are inscribed in the proper space for the particular material being counted, so that the count obtained by both operators for the particular articles or material for which an inventory count is desired will appear in the appropriate spaces opposite one another on forms 18 and 10. This second operator continues the count of the inventory, and when completed will turn the manifold assembly as it then exists over to the accounting department, where the inventory count of the two operators will be compared.

This is readily and easily accomplished in the use of the present manifold assembly for the reason that by gripping the manifold assembly at or adjacent the marginal edge thereof at the securing means 6 and 8 and applying a quick outward and opposite force thereto, the assembly will be torn or severed along the weakened severance lines 30 and 32 into two parts, such as shown in Figure 5 of the drawing. That portion of the assembly to the right as shown in Figure 5 is constituted by a part of the copy record sheet 16 and the original record sheet 11 with the inscriptions indicating inventory count by both operators disposed opposite one another for ready comparison. In the illustration, the two counts as recorded by the two operators conform to one another, and no variation exists between the two, but since these counts are independent there may be variations in the recorded counts for the various articles or material forming the inventory, which would be clearly apparent by a comparison of the two as they appear side by side in Figure 5 of the drawing. Any variation can then be checked by the accounting department to determine the reasons therefor.

While I have herein described and upon the drawings shown an illustrative embodiment of the invention, it is to be understood that the invention is not limited thereto but may comprehend other constructions, arrangements of parts, details and features without departing from the spirit of the invention.

I claim:

1. A manifold assembly or the like, comprising an original record sheet having an area on one side thereof provided with transfer material, a copy record sheet disposed in association with said transfer material and secured to said original record sheet on opposite sides of said transfer material, and said original and copy record sheets on opposite sides of said transfer material having weakened severance lines within the boundaries of the secured portions of the original and copy record sheets whereby a part of said original record sheet and an attached part of said copy record sheet may be detached from another part of said original record sheet and another part of said copy record sheet attached thereto.

2. A manifold assembly or the like, comprising an original record sheet having an area provided with a form suitable for recording information thereon and an adjacent area provided with transfer material, a copy record sheet disposed in association with said transfer material for receiving recordations from said original record

sheet through said transfer material, means securing said copy record sheet to said original record sheet on opposed sides of said transfer material, and said original and copy record sheets on opposite sides of said transfer material having weakened severance lines within the boundaries of said securing means whereby a part of said original record sheet and an attached part of said copy record sheet may be detached from another part of said original record sheet and another part of said copy record sheet attached thereto.

3. A manifold assembly or the like, comprising an original record sheet having an area provided with a form suitable for recording information thereon and an adjacent area provided with blank copy, said original record sheet on its opposed face having transfer material associated with said blank copy, a copy record sheet disposed in association with said transfer material for receiving recordations from said original record sheet through said transfer material, means securing said copy record sheet to said original record sheet on opposed sides of said transfer material, and said original and copy record sheets on opposite sides of said transfer material having weakened severance lines within the boundaries of said securing means whereby a part of said original record sheet and an attached part of said copy record sheet may be detached from another part of said original record sheet and another part of said copy record sheet attached thereto.

4. A manifold assembly or the like, comprising an original record sheet having an area for recording information thereon and an adjacent area provided with transfer material, a copy record sheet disposed in underlying relation to said original record sheet and in transfer relation to said transfer material, said original record sheet having a marginal edge secured to said copy record sheet on one side of said transfer material and said copy record sheet having a marginal edge secured to said original record sheet on the other side of said transfer material, and said original and copy record sheets on opposite sides of said transfer material having weakened severance lines whereby a part of said original record sheet and an attached part of said copy record sheet may be detached from another part of said original record sheet and another part of said copy record sheet attached thereto.

5. A manifold assembly or the like, comprising overlapping record sheets, one of said sheets having a portion forming an original record sheet and another portion forming a transfer sheet provided with transfer material in superimposed relation to the second record sheet, the other of said record sheets having a portion forming a copy record sheet underlying said transfer portion of the other of said record sheets and another portion forming an original record sheet,

means securing said overlapped record sheets together on opposite sides of said transfer material, said second-named record sheet being foldable in superimposed relation to said transfer sheet whereby inscriptions placed thereon are transferred to said copy record sheet, and said record sheets inwardly of said securing means having weakened severance lines whereby said transfer sheet and an attached portion of said copy record sheet may be detached from said first-named original record sheet and an attached portion of said copy record sheet.

6. A manifold assembly or the like, comprising overlapping record sheets, one of said sheets having a portion forming an original record sheet and another portion forming a transfer sheet provided with transfer material in superimposed relation to the second record sheet, the other of said record sheets having a portion forming a copy record sheet underlying said transfer portion of the other of said record sheets and another portion forming an original record sheet, means securing said overlapped record sheets together on opposite sides of said transfer material, said second-named record sheet being foldable in superimposed relation to said transfer sheet whereby inscriptions placed thereon are transferred to said copy record sheet, said second-named record sheet at the fold having a weakened severance line to facilitate removal of the said second-named original record sheet, and said record sheets inwardly of said securing means having weakened severance lines whereby said transfer sheet and an attached portion of said copy record sheet may be detached from said first-named original record sheet and an attached portion of said copy record sheet.

7. A manifold assembly or the like, comprising overlapping record sheets, one of said sheets having a portion forming an original record sheet and another portion forming a transfer sheet provided with transfer material in superimposed relation to the second record sheet, the other of said record sheets having a portion forming a copy record sheet underlying said transfer portion of the other of said record sheets and another portion forming an original record sheet, said transfer sheet above said transfer material having blank copy, means securing said overlapped record sheets together on opposite sides of said transfer material, said second-named record sheet being foldable in superimposed relation to said transfer sheet whereby inscriptions placed thereon are transferred to said copy record sheet, and said record sheets inwardly of said securing means having weakened severance lines whereby said transfer sheet and an attached portion of said copy record sheet may be detached from said first-named original record sheet and an attached portion of said copy record sheet.

JOHN R. KEELEY.
